UNITED STATES PATENT OFFICE.

ARTHUR J. THOWLESS, OF NEWARK, NEW JERSEY.

DEVICE FOR CLEANING FLUID-PENS.

SPECIFICATION forming part of Letters Patent No. 768,637, dated August 30, 1904.

Application filed June 18, 1904. Serial No. 213,196. (No model.)

To all whom it may concern:

Be it known that I, ARTHUR J. THOWLESS, a subject of the King of Great Britain, residing at Newark, in the county of Essex and State 5 of New Jersey, have invented new and useful Improvements in Devices for Cleaning Fluid-Pens, of which the following is a specification.

My invention relates to an improvement in the means for cleaning the pen-holding part 10 of a fountain-pen, so that it can be thoroughly washed and cleaned in a simple and satisfactory manner.

The object of this invention is to produce a device which shall be simple in construction, cheap to manufacture, and which shall be effectual in all respects in the performance 15 of its functions.

With these objects in view the invention consists of certain novel features of construction and combinations and arrangement of parts as hereinafter set forth and claimed.

In the accompanying drawings, Figure 1 is a front elevation, showing the pen-holding part of a fountain-pen and the cleaning device 25 detached from each other. Fig. 2 is a cross-sectional view of Fig. 1, with the difference that Fig. 2 shows the pen-holding part and the cleaning device attached. Fig. 3 is a cross-sectional view of the plug C, showing a screw-thread E inside. Fig. 4 is a sectional view of the plug C, but showing a screw-thread L outside the plug C. Fig. 5 is a cross-section of the plug C with slightly-tapering part J. Fig. 6 is a sectional view 30 of the plug C and portion of pen-holding part I.

Like letters of reference designate corresponding parts in the several views of the drawings, and in this respect A represents 40 a bulb made of rubber or some other material possessing the same general characteristics and may be round or of other suitable shape, having an elongated part B, which may taper from the bulb A, so that it fits tightly on the elongated part D of the plug C. This part D should be of sufficient length and be inclosed by the elongated part B in such a manner that a very tight and close attachment may be held between them, as other-

wise the perfect working of the cleaner might 50 be marred.

The plug C is hollow and may be made of metal, rubber, porcelain, or other suitable material and has a screw-thread E cut or otherwise formed on the inner part of it of 55 a size suitable for engaging with the screw-thread H, which is cut on the pen-holding part of a fountain-pen and is represented as I. In some cases and to fit certain makes of fountain-pens it may be found necessary to 60 form a screw-thread on the outer part of the plug C, as is shown in Fig. 4 at L, or even to do without a screw-thread entirely and instead make that part of the plug C as a closely-fitted tapered piece, as in Fig. 5 at J. 65

F shows a small space between the pen-holding part I and that part of the plug C which comes in contact with it, and this contact part is shown at G. The screw-thread H, Fig. 1, is shown as formed on the outside 70 of pen-holding part I and screws into the thread E.

The letter K shows the ordinary ink-feed, while the letter P is the writing pen-point itself in its natural position. 75

M is the shoulder, extending up from the plug C, and N is a more or less flexible washer placed between the parts to make a tight joint.

In carrying out the invention, as fountain-pens may be made of various sizes, so the 80 cleaning device may be formed of sizes to suit different pens. Also the operative parts can be made of any suitable material for the proper working of the invention.

When the parts are properly constructed 85 and arranged, there is formed a device that will serve to clean the pen-holding part of fountain-pens or similar articles in a simple, efficient, and satisfactory manner.

To attain a cleaning result, the pen-holding 90 part of a fountain-pen is removed from the ink reservoir or barrel, and then by attaching the cleaning device to the pen-holding part and immersing the pen in water or other cleaning liquid a pressure of the fingers will 95 cause the bulb to collapse. Then by removing the pressure the cleaning liquid will flow through the pen-holding part to the bulb A,

passing through the elongated part D on its way, and can then be forced out again by pressure on the bulb A. This is repeated again and again until the cleaning is completed, 5 when the device may be removed and the pen-holding part restored to its place on the barrel. As it may be necessary to use considerable pressure to force the cleaning fluid back from the bulb A, it is needful to see that proper 10 union is made between the different parts. Therefore the joint between the part B and the plug C should in all cases be a good one, or the exerted pressure might tend to force the part B off the plug C. So for further 15 protection a sufficient length should be given to the elongated part D to obviate the difficulty referred to. It might also be found advisable in some cases to attach the part B on the part D with a small quantity of cement. 20

In this specification the words "pen-holding part" are used to denote that part of a fountain-pen which can be separated from the ink-barrel and is to be understood as including 25 the ink-feeding part. Furthermore, in the operation of cleaning the pen-holding part the device cleans the pen-point at the same time unless actually removed, which is not at all necessary.

30 Having thus described my invention, what I claim is—

1. A device for cleaning the pen-holding part of fountain-pens comprising a bulb adapted to receive and discharge liquids, the outlet 35 of which is tightly compressed on a plug, said plug having a screw-thread formed to engage with a corresponding screw-thread contained

in the pen-holding part, substantially as shown and set forth.

2. A device for cleaning the pen-holding part of fountain-pens and similar articles comprising a collapsible bulb adapted to receive and discharge liquids by compression and means fastened thereto whereby it can be attached to the pen-holding part of a fountain- 45 pen.

3. A device for cleaning the pen-holding part of a fountain - pen comprising a bulb adapted to receive and discharge liquids, having an elongated tube portion and means for 50 attaching it to the pen-holding part of a fountain-pen.

4. A device for cleaning the pen-holding part of a fountain-pen, comprising a bulb, made of rubber or other similar material, having 55 an elongated tube portion, a plug with an elongation which passes into the bulb-tube and having on its other end suitable means for connecting the plug with the pen-holding part of a fountain-pen.

5. In a device for cleaning the pen-holding part of a fountain-pen the combination with a collapsible bulb of a tube and a plug for securely attaching the same to the pen-holding part of a fountain-pen. 60

6. A new article of manufacture comprising a device for cleaning the pen-holding part of fountain-pens, having within itself and fastened thereto means for enabling it to be closely attached to the pen-holding part. 65
